ASSIGNORS TO THE ROCHESTER FOLDING BOX CO., OF ROCHESTER, NEW YORK, A
CORPORATION OF NEW YORK

COLLAPSIBLE PLAYHOUSE

Application filed April 25, 1929. Serial No. 358,124.

This invention relates to a structure capable of being erected into a playhouse of substantial dimensions and adapted to be collapsed into a compact article for purposes of transportation or storing. An object of the invention is the provision of an article of this character which is generally improved and more satisfactory than similar articles heretofore known.

Another object of the invention is the provision of a structure which is light and easy to handle, which may be assembled or erected easily and quickly even by inexperienced persons such as children, which when erected is held securely against accidental collapse, and yet which may be easily collapsed when desired to form a compact article.

A further object of the invention is the provision of a collapsible playhouse so designed and constructed that it may be built of fairly large dimensions, for example, large enough so that children may actually enter and play within the playhouse, and yet which when collapsed will be light and compact and easy to transport or to store.

To these and other ends the invention resides in certain improvements and combinations of parts, all as will be hereinafter more fully described, the novel features being pointed out in the claims at the end of this specification.

In the drawings:

Fig. 1 is a perspective view of a playhouse constructed in accordance with a preferred embodiment of the invention, showing it in erected position;

Fig. 2 is a vertical cross section taken transversely through the erected playhouse;

Fig. 3 is a perspective view of the bottom or floor member removed from the playhouse;

Fig. 4 is a perspective view of the wall structure of the playhouse, showing it collapsed

Fig. 5 is a perspective view of the roof member, showing it removed from the rest of the playhouse and partially collapsed, and

Fig. 6 is a horizontal section through the playhouse in its erected position.

Similar reference numerals throughout the several views indicate the same parts.

Referring now especially to Figs. 1 and 6 of the drawings, the collapsible playhouse constructed in accordance with the present invention comprises a wall structure having what might be termed end walls or wall portions 10 and side walls or wall portions 11. These walls, and also the roof member and floor member, are preferably constructed of corrugated board, or similar light, fairly stiff and easily workable material, although it is contemplated that other materials may be used if desired.

The various wall portions are connected to each other at points corresponding to the corners of the house, the connections preferably being formed by strips 12 of paper or the like which form hinges, so that the walls may be said to be hinged to each other. In addition to the hinged joints at the corners of the structure, the side walls 11 are provided with vertical joints at intermediate points, these joints preferably being formed by the score lines 13 at the mid points of the side walls. These score lines weaken the material so that a hinge is formed, permitting the two portions of each side wall 11 to be doubled back upon each other.

When the playhouse is assembled or erected, the walls are in position to form a rectangular structure such as is shown in Figs. 1 and 6. A floor member such as is shown in Fig. 3 may be used not only to provide a bottom for the structure, but also to hold the walls in erected position and to prevent accidental collapse thereof. This floor member comprises a flat member 15 having a score line 16 substantially down the center thereof to form a joint so that the floor member may be folded up. The floor member also has score lines 17 forming joints to permit marginal portions 18 of the member to be bent upwardly at an angle to the flat bottom portion 15.

When the playhouse is assembled, the floor member is placed within the walls so that it covers substantially the entire area embraced by the walls, and the marginal portions 18 extend upwardly a short distance along the inner surfaces of the walls, in the manner

illustrated clearly in Fig. 2. These marginal portions 18 form substantial bearing areas in contact with the side walls 11 of the building. The presence of the score line or joint 16 in the floor member not only permits this floor member to be folded up when the house is collapsed so that it occupies a substantially less area than the area of the house when erected, but furthermore is of advantage in 10 facilitating the easy insertion of the floor member when the house is being assembled. The floor member may be slightly bent at this joint while it is being put within the walls, so as to decrease the width of the floor member. It may then be flattened out by pressing downwardly upon the center of the floor after the edges have been properly positioned at the bottoms of the side walls 11, and this will produce a sort of toggle action, 20 forcing the edges of the floor tightly against the walls so that some tension is placed upon the walls and they are held firmly in position. Obviously, the presence of the floor member prevents accidental collapse of the structure. 25 Gable portions 20 are provided at the tops of the end walls 10 of the house, these gable portions preferably being formed integrally with the end walls 10 and hinged by means of score lines 21 so that they may be folded down against the end walls when the building is collapsed. A roof member 22 is formed preferably of one integral piece scored centrally at 23 at the ridge of the roof so that it may be bent to fit over the gable portions 30 20 and to form an A-roof as shown in Figs. 1 and 2. The roof, when in position, acts to hold the gable members 20 against accidental collapse. This may be accomplished by providing members such as the pins 24 passing 35 through the roof and into the gable members 20, thus pinning the gable members and roof securely together. 40

A door 30 is provided in one of the end walls 10, being formed by slits 31 at the top 45 and one side of the door, and a score line 32 along the other side to provide a hinge for the door.

A plurality of windows is also provided, the window openings preferably not being 50 completely cut out but being formed by means of top and bottom slits 35, a vertical slit 36 and score lines 37 providing hinged joints so that shutters are formed which may be opened either inwardly or outwardly to 55 open the windows, or which may be closed into the plane of the wall to close the window openings completely.

To collapse the playhouse, the pins 24 holding the roof 22 to the gables 20 are first 60 removed, so that the roof may be taken off and folded up to occupy a comparatively small space. It is shown partially folded in Fig. 5, but the free edges are slightly separated in this figure to illustrate the construction more clearly.

After the roof is removed, the floor 15 may be taken out and folded up in the same way that the roof was folded, the marginal portions 18 being turned down so that they lie substantially in a plane. The removal of the floor member allows the walls to be collapsed. This is done by moving the central portions of the side walls 11 inwardly toward each other so that these walls bend at the score lines 13, the end walls 10 moving straight toward each other and remaining substantially parallel to each other. Fig. 4 illustrates the wall structure partially collapsed, and shows what a small space it occupies in comparison to the space of the erected house. Before or after the walls are collapsed, the gable portions 20 may be folded down so as to lie against the end wall portions 10. 75 80 85

Since the wall structure, the floor member and the roof member each fold up substantially into a plane having a comparatively small area, it will be seen that the playhouse when collapsed is extremely compact, and may be easily transported or stored notwithstanding that the play house may be of large enough dimensions when erected so that children may play inside it. 90

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims. 100

We claim as our invention:

1. A collapsible playhouse comprising end wall and side wall portions hinged to each other at points corresponding to the corners of the house and arranged to be erected into a rectangular wall structure, said side wall portions having substantially vertical joints so that said wall structure may be collapsed by doubling said side walls upon themselves and by moving the end walls toward each other, a collapsible floor member arranged to fit within said wall structure when it is in erected position and acting to hold the walls in such position and prevent collapsing thereof, said floor member having an intermediate joint so that when the floor member is removed to permit the house to be collapsed the floor member may be folded to occupy a substantially smaller area than the area of the house when erected, gable portions hinged to the upper edges of said end wall portions and arranged to extend upwardly therefrom when the house is erected or to be folded down against said end wall portions when the house is collapsed, and a roof member arranged to hold said gable portions in their erected position. 110 115 120 125 130

2. A collapsible playhouse comprising end

wall and side wall portions hinged to each other at points corresponding to the corners of the house and arranged to be erected into a rectangular wall structure, said side wall portions having substantially vertical joints intermediate the ends thereof so that said wall structure may be collapsed by doubling said side walls upon themselves and by moving the end walls toward each other, windows in certain of said walls formed by slits and score lines placed so as to provide hinged shutters integral with the walls, one of said walls having slits and a score line placed so as to provide a hinged door integral with said wall, a collapsible floor member arranged to fit within said wall structure when it is in the erected position and acting to hold the walls in such position and preventing collapse, said floor member comprising a central portion covering substantially the entire area enclosed by said wall structure when erected, and marginal portions hinged to opposite edges of said central portion and arranged to extend upwardly along the inner surfaces of opposite walls of the playhouse, said cen-

tral portion having an intermediate joint so that when the floor member is removed to permit the house to be collapsed the floor member may be folded to occupy a substantially smaller area than the area of the house when erected and so that when the house is erected the floor member may be inserted in a partially folded condition with two edges on the supporting surface on which the house rests and the central portion may then be depressed into contact with such surface in order to expand the walls fully by a toggle action, gable portions hinged to the upper edges of said end wall portions and arranged to extend upwardly therefrom when the house is erected or to be folded down against said end wall portions when the house is collapsed, a roof member fitting said gable portions in the extended position of the latter, and a plurality of pins passing through said roof member to hold said gable portions in upright position.

WILBER E. BOWERSOCK.
